UNITED STATES PATENT OFFICE.

PAUL EDGAR THOMASON, OF CHARLOTTE, NORTH CAROLINA.

MOVING-PICTURE SCREEN.

1,059,236.

Specification of Letters Patent.

Patented Apr. 15, 1913.

Application filed January 25, 1912. Serial No. 673,285.

To all whom it may concern:

Be it known that I, PAUL EDGAR THOMASON, a citizen of the United States, and a resident of Charlotte, in the county of 5 Mecklenburg and State of North Carolina, have invented a new and useful Improvement in Moving-Picture Screens, of which the following is a specification.

My invention is an improvement in moving picture screens, and has for its object 10 the provision of a screen of the character specified which may be operated to present a plain white surface for receiving the display of the pictures, or which may be operated to present a display of advertisements or the like when the pictures are not being displayed.

In the drawings:—Figure 1 is a front view of the improvement with the screen in place; Fig. 2 is a side view; and Fig. 3 is a front view with the screen out of place.

In the embodiment of the invention the curtain is in the form of an endless belt 1, supported by an upper roller 2, and a lower 25 roller 3. The roller 2 is provided with journal pins 4 journaled in bearings 5 in brackets 6 on the ceiling 7 or other suitable place. The lower roller 3 has journal pins 8 and 9, journaled in brackets 10 and 11 30 respectively on the floor 12 or other suitable place. A worm gear wheel 12 is secured to pin 9 and a worm 13 on a worm shaft 14 is in engagement with the wheel 12. The worm shaft is journaled in bearings 15 on 35 the bracket 11 before mentioned. The worm

shaft 14 is in alinement with the shaft 16 of a suitable motor 17 electric motor in the present instance, and a suitable clutch 18 is provided for connecting the shafts. A suitable switch (not shown), is arranged in 40 the operating booth near the operator for starting the motor and leads 19 lead from the motor to the switch.

The belt 1 is provided with a plain portion 20, and with a portion 21 for receiving 45 advertisements or the like, and when the pictures are not being shown, the portion 21 is placed in position in front of the audience. When the pictures are being shown, the plain portion 20 is in front of the audience. The operator can bring either portion 50 into view by starting the motor and turning the lower roller. When the belt winds far enough the motor is stopped until the belt is to be again changed. 55

I claim:—

A device of the character specified, comprising an endless belt having on the outer face thereof a display portion and a plain portion of approximately the same size, upper and lower supporting rollers for the belt, a worm gear wheel secured to one end of one roller, a motor having a worm shaft provided with a worm meshing with the worm wheel, and means for controlling the 60 motor from a distance. 65

PAUL EDGAR THOMASON.
